Application February 4, 1952, Serial No. 269,853

8 Claims. (Cl. 5—82)

The present invention relates to rescue apparatus and particularly to a device in the general nature of a stretcher which has a universal application in rescue operations.

Many types of rescue apparatus have been devised but in the past many types of rescue operations could not be performed with a single piece of apparatus, some apparatus being adapted to one type of operation, some to another. Thus the commonly used stretcher having rigid side members is not adapted to operations requiring the turning of sharp corners. Nor is it adapted to operations wherein vertical transportation or removal over rough terrain is involved.

Also, such types of devices as the Stokes litter and army type stretcher have been frequently used but also have many limitations. For example, these devices cannot be used where an accident victim is in a location with limited head room since they have either upstanding sides or "legs" making it impossible to place the victim in the litter without first moving him to a place where there is sufficient head room to perform the operation, especially if the victim be obese. Nor is the Stokes type usable when the victim is unusually tall.

Additionally, most types of rescue device in common use are rigid and cannot be readily transported, and if the entire device is not rigid there are still rigid members which are necessary to the use of the device.

There are, of course, situations wherein it is necessary that the device be rigid. For example, it may be that the person to be transported has a broken back or broken neck. The present device, unlike the ordinary ambulance stretcher, is provided with a means whereby it may be rendered rigid when necessary.

Commonly used devices such as the Stokes litter or the army type stretcher previously mentioned have the limitation that they cannot be readily used in other than the horizontal position and consequently situations frequently arise where it is impossible to turn a corner. The device of my invention is adapted to use as a chair litter and may therefore be utilized in many situations where sharp corners make the use of other types impossible.

Situations also frequently arise where an accident victim has suffered a fracture of a limb and it is essential that the fractured member be placed in traction at the earliest possible moment. My device is provided with readily operable means whereby such traction may be exerted.

It is an object of my invention to provide a rescue device which is universally useful and which is so designed as to be readily operable.

It is another object of my invention to provide a rescue device adapted for use when it is necessary to lower or raise the device vertically or substantially vertically.

It is another object of my invention to provide a device which, while usable in a vertical position for raising and lowering operations, may still be utilized in the normal carrying operation or for raising and lowering operations in a horizontal position.

2

It is another object of my invention to provide a rescue device having elements designed to enclose the victim and protect him from weather, falling debris, and the like, while at the same time providing ample space for ingress of air and leaving the face exposed so that the victim, if conscious, will not be psychologically affected by being completely enclosed.

It is a still further object of the invention to render the enclosing means adjustable in such a manner that the rescue device may form a complete enclosure for use particularly in case the person transported is already dead.

It is a still further object of my invention to provide a means for exerting traction upon a broken limb of a victim to be transported in the device.

15 Other objects and features of the invention will be apparent when the following description is considered in connection with the annexed drawings, in which:

Figure 1 is a top plan view of the device in its closed condition but ready for use, that is, unrolled rather than 20 rolled for transportation purposes;

Figure 2 is a bottom plan view of the device in the same condition as described in Figure 1;

Figure 3 is a top plan view of the device in its open condition save that certain of the flaps are still closed, 25 these flaps being shown open by dotted lines;

Figure 4 is a fragmentary cross-sectional view of the device of Figure 3, the view being taken on the plane of the line 4—4 of Figure 3;

Figure 5 is a perspective view showing the device rolled 30 up and inserted in its carrying bag;

Figure 6 is a fragmentary view of the lower portion of the rescue device showing the means for anchoring the feet of the victim so that the rescue bag may be used in work involving vertical transportation;

35 Figure 7 is a fragmentary plan view of the device showing the use thereof for applying traction to a broken leg; and

Figure 8 is a fragmentary view of the upper portion 40 of the device showing the mode of immobilizing the head of the victim such as would be utilized in the event the victim had a broken neck.

Referring now to the drawings, and particularly to Figure 4, the device comprises two layers of material 10 and 11 which material may, for example, be heavy waterproof canvas. The layer 10 is wrapped around a heavy 45 rope 12 at each edge the edge portion being stitched to the main portion of the fabric 10 to completely enclose the rope 12 and cause the rope to be firmly held at the edges of the layer 10 of the material. The stitching also passes through the layer of material 11 as well as through the flap portions 13 and 14.

The rope 12, as seen in Figures 1 through 3, is continuous, extending along the edges of the device from the foot portion thereof to the apex at the head. The 50 rope thus reinforces the edges and provides a gripping means at all points therealong. At the apex of the device there is a steel ring 15 which ring is "whipped" to the fabric layers 10 and 11. Extending downwardly from the ring 15 along a center line of the device is a reinforcing webbing strip 16 which strip terminates about one-third of the way to the foot of the device. This strip 55 16 is sewn to the fabric layer 10 on the rear surface thereof and serves to distribute force exerted on the ring 15 to the fabric.

This manner of distributing the load to the fabric assures that the device will not curl about its longitudinal center. Moreover, since the apex of the rope 12 passes over the upper edge of the ring 15, if there should be any 60 failure of the whipping or stitching by which the ring is held to the fabric layers the rope 12 would then take a portion of the load.

Extending upwardly at an angle to the reinforcing strip 16 are two pairs of reinforcing strips 17 and 18. Each of these pairs is sewn to the rear surface of the fabric 10 and each is formed from a single strip of fabric thus providing the handles 19 and 20. These fabric strips in addition to forming handles, as stated, likewise serve to distribute load placed upon the ring 15 to the body of the fabric 10.

As has previously been mentioned, the basic structure thus far described is provided with flaps 13 and 14 which flaps are sewn to the edges of the fabric strips 10 and 11. These flaps 13 and 14 are designed to serve as covers for a victim placed upon the fabric layer 10. In addition to the flaps 14 and 13 there is provided a foot flap 21 which is stitched to the fabric layers 10 and 11 and to the flaps 13 and 14 along its lower edge. The flap 21 is, as indicated, particularly intended for covering the feet and lower legs of the victim. Both the side flaps and foot flaps are adjustable to properly cover persons of diverse physical characteristics—thin or fat, short or tall.

Each of the flaps 13 and 14 is provided with a diagonally folded portion which may be termed a secondary flap designated respectively 22 and 23, see Figure 3. Flaps 22 and 23 are normally not utilized in covering a victim, but would be used in the event that the person transported is already dead or, in some instances, when due to falling debris it is necessary to protect the head of the victim.

Fixed to the front or upper surface of the fabric layer 10 is a foldable hood 24 which comprises a generally rectangular fabric member having folds therein as indicated at 25 and 26 to form a hood, which has a secondary flap 29. Hood 24 may be utilized to cover the head in the event of inclement weather or of falling debris, or hood 24, together with flap 29, may cover the face and head.

Likewise stitched to the fabric 10 at a point corresponding to the chest area of the body to be transported is a strap 27 which is stitched along a portion only of its length the two ends being left free so that the body may be encircled by the strap which is provided with a buckle 28 of any suitable kind. Strap 27 may be used as a traction anchor for broken arms and also maintaining the position and preventing shifting of a person transported.

Spaced along the length of the device are carrying handles or loops 30, these handles being formed of webbing which extends entirely across the device being stitched to the upper surface of the lower layer 11 of fabric material. That is, each pair of handles 30, one on either side of the device, forms, in addition, two reinforcing straps extending completely across the device.

The device can readily be converted into a litter for transportation over rough terrain by inserting saplings or poles of approximately ten foot lengths through the loops 19 and 30 and 20 and 30. In this connection it should be noticed that the loops 19 and 20 are longer than the loops 30 so that poles inserted through the various loops on opposite sides of the device will extend substantially parallel to the longitudinal axis.

The uppermost pair of loops 30 and the lowermost pair of loops 30 may be utilized in cooperation with a pair of slings to convert the device into a basket type carrier which may be then utilized in a substantially horizontal position for raising and lowering operations. That is, a rope sling would extend through the uppermost and lowermost loops 30 on each side of the device, the four eyes in which the two rope slings terminate being then placed on the hook of a block and tackle or a similar device to effect the raising or lowering operation.

The straps 30 are located at carefully selected areas in order to make it possible to utilize the device as a chair litter. Thus the upper pair of straps 30 is located in the area of the shoulder blades and the second pair in the area of the buttocks whereby carriers of the device may readily cause it to assume the shape of a chair in order

to turn sharp corners which it would otherwise be impossible to do.

Straps 30 may also be utilized in the event that the device is to be lowered down a ladder. In this case, 5 short lengths of board or pole are inserted through loops of the uppermost straps 30 and likewise through the loops of the straps 30, third from the top in the region of the thighs. These form rigid supports which may rest on the rails of the ladder so that a person may be lowered down the ladder without interference with the ladder rungs. Furthermore, the board or pole lengths may be adjusted to the width of the ladder whereby a ladder of any standard width may be utilized as the guiding member.

The fabric layer 11 extends to a point adjacent the 15 head area and there terminates, being stitched to the fabric 10 only along its edges and not at its top or bottom. There is thus formed a pocket into which a rigid member or members may be inserted so as to make it possible to transport a victim who has met with an accident requiring that the back area be immobilized, for example, one who has sustained a broken back or neck. There is no necessity of providing a permanent rigid member since there is seldom if ever a situation where it is not possible to secure a board or like device as for example a piece of baseboard or a door jamb or a portion 25 of a desk to act as a splint. In Figures 2 and 4 the splint is shown as comprised of three boards 39.

Means are provided for holding the flaps 13 and 14 in closed position, and for holding a person in place in 30 the device or on the device. These means comprise webbing straps 31 adapted to extend transversely of the device above the folded flaps. The straps 31 are made adjustable by means of buckles 32 which buckles are fastened to the margin of the device by means of short 35 lengths of strap 33. At the opposite side of the device four cooperating rings 34 are positioned, being secured to the fabric through the medium of short lengths of strap 35. Each of the straps 31 passes through an eye 36 in a snap hook 37, the hook being adapted to cooperate 40 with the ring 34. In this manner the straps may be rapidly loosened or put in place while at the same time they are adjustable by use of the buckle 32.

Although straps 31 are shown as passing directly across 45 the device, they may be crossed in a diagonal fashion to prevent pressure on an area which has been injured. In the event of injury in the chest area, for example, the two upper straps 31 would be crossed over each other to prevent pressure on the injured portion of the chest.

In a manner similar to that described above for the 50 fastening of the hooks 37 and the buckles 32, pairs of rings 40 are fastened to the fabric, one pair in the chest area and one in the foot area. The pairs of rings 40 in the chest area are intended for use in applying traction as will be hereinafter explained, while those in the 55 foot area are for a purpose to be described.

When such vertical lowering or lifting is to be performed, it is desirable that the person being rescued be firmly anchored within the enclosure formed by the various flaps hereinbefore described so that he cannot by any 60 chance move vertically and slide out of the device. For this purpose two straps 41 are provided, which straps are provided with buckles 42 for adjusting the length thereof, the straps passing through an anchor ring 43 which is secured by a short piece of webbing or like material 44 to the fabric layer 11. Each strap 41 is also provided with a snap hook 45 adapted to cooperate 65 with one of the lower pair of rings 40. Thus the straps 41 may be crossed over beneath and above the feet and fixed to the rings 40 thereby forming a support for the feet, which will assure the safety of the rescue operation involving vertical transportation. In Figure 6, for clarity of illustration, the flaps 13, 14 are shown folded under the legs, but ordinarily these flaps would cover the legs.

As will be obvious, the device thus far described may 70 be utilized in all the manners described for both adults

and children. In the event, for example, that a child is to be transported in a horizontal position the child may be laid on the open device and the flaps folded as heretofore described after which the entire base of the device may be again folded upwardly before the straps are fastened. This will insure the safety of the child.

31 are fastened. This will serve to reduce the size of the device to that of the child so that it may be readily carried. Furthermore, if the child is to be lowered or raised in a vertical position the straps 41 may again be utilized, in this event being fastened to the upper ones of the two pairs of rings 40 rather than to the lower ones.

The ring 43 is also utilized for various other purposes, thus in the event that it is necessary, due to the lack of head room, to slide the rescue device across the floor or along the ground, a rope may be attached to this ring 43 and the device pulled feet first by this means, and if necessary it is even possible to lower the entire device by attaching a rope to the ring 43 although generally speaking it is preferable that lowering or raising operations be not performed with the victim's head pointed downward.

Should the victim have a compound fracture of a leg one of the straps 41 may be removed from the ring 43 and a loop thereof placed about the injured leg at the thigh area, the strap being attached to that one of the upper pair of rings 40 on the side of the fractured member. This strap then holds the torso firmly in place. The second of the straps 41 is then wrapped about the foot, passed through the ring 43, and tightened to put a pull on the leg to thereby place the leg in traction, preventing further injury as a result of such a compound fracture. This arrangement is shown in Figure 7. In this figure the person being rescued is shown lying on the folded flaps rather than beneath them. However, it is entirely possible to utilize traction with the flaps over the victim save that the foot flap 21 must be placed beneath the legs rather than over them.

Straps 41 are sufficiently long so that an arm having a compound fracture may be treated in similar manner by looping one of the straps 41 about the wrist and through the ring 43 and tightening it. Chest strap 27 serves as the anchor for application of arm traction.

Referring now to Figure 8, there is shown therein a mode of utilizing the device to hold the head in a fixed position which is sometimes essential, as for example, when the victim has a broken neck. In this arrangement a blanket, indicated at 46, is rolled army pack manner and inserted beneath the head cover or hood 24. This forms a pocket in which the head rests and which prevents shifting movements thereof with respect to the torso which, of course, is firmly held in place by means of the strap 27. If a head pillow is required a blanket is placed beneath hood 24.

The rescue pack of my invention may also be used for carrying by a single carrier. The pack may be stood in a vertical position, the rescuer then placing his back against the victim's back and, by grasping the upper ones of the loops 30, can carry the casualty.

The rescue pack as described hereinabove is usable in many situations where other types fail. In addition to the situations already mentioned, such problems of vertical transportation as arise when mine shafts, dumbwaiters, etc. have to be utilized are readily solved with this device. Such devices as the Stokes litter and the arm stretcher are not usable for example in a dumbwaiter since their rigidity prevents the insertion thereof through the dumbwaiter doors as does the thickness brought about by the upstanding sides or the legs. Moreover the army type stretcher is stretched into its position of use by means of toggle members which members are readily displaced during vertical movement of the device causing the stretcher to collapse. As indicated, the device of my invention obviates such difficulties.

While I have described the preferred form of my in-

vention, it will be understood that many modifications of the structure may be made within the scope of the invention. Therefore I wish to be limited not by the foregoing description, but on the contrary, solely by the claims granted to me.

What is claimed is:

- What is claimed is:

  1. In a rescue device of the class described, in combination, a generally rectangular piece of fabric, said fabric coming to a point at one end and being gradually tapered toward the opposite end to form an outline generally that of a recumbent person to be transported, a second fabric piece underlying said first piece and fixed thereto at its side margins, said second fabric piece reinforcing the first and forming with said first piece an open ended pocket to receive a splint, a rope extending along the top and side margins of the device and fixed to both said fabric layers, said rope forming a hand hold, a plurality of carrying straps extending transversely of said device in pairs, each pair forming a loop at each of the opposite edges of said device, said reinforcing and carrying straps being connected to the lower layer of fabric throughout the transverse extent thereof and being also connected to the upper fabric layer at the edges of that layer, and serving to reinforce the fabric, a load carrying ring fixed to both said fabric layers adjacent the upper point thereof, and a pair of covering flaps secured to said fabric layers at the margins thereof, said covering flaps being adapted to fold over said fabric and extending approximately to the shoulders of a person to be transported on the device.
  2. A device as claimed in claim 1, characterized in that said covering flaps terminate at their upper edges along lines inclined diagonally across the device and that said covering flaps have secondary flaps secured thereto along said diagonally inclined lines, said secondary flaps when in their unfolded position serving to cover the face and head of a person to be transported on the device.
  3. A device as claimed in claim 1, characterized in that a ring is secured to the underlying fabric piece adjacent the lower edge thereof and approximately on the longitudinal center line and additional pairs of rings are secured to the side margins of the overlying piece of fabric, one pair adjacent the chest area of a person to be transported and the other adjacent the foot area, said rings being adapted to receive adjustable straps for anchoring the feet of a person to be transported in place and for anchoring the person to be transported in position with traction applied to a fractured limb.
  4. In a rescue device for supporting a body to be transported comprising a substantially rectangular first member comprising a heavy waterproof fabric and having a head portion and a foot portion and converging at the head portion into an apex, a rope extending the full length of said fabric from the foot portion to the head portion to said apex and secured to all the edges of said canvas for reinforcing all the edges and for providing a gripping means at all points thereon, a load-receiving metallic member at the apex of said member, a first reinforcing member extending from said load receiving metallic member longitudinally along said first member for distributing the forces exerted on said load receiving metallic member to prevent curling of said first member along its longitudinal center when load is applied thereto, said rope extending to and being secured to said load receiving metallic member for taking a portion of the load, a plurality of reinforcing strips extending angularly from said first reinforcing member for forming handles and also for distributing the load on said first load receiving member, flaps extending along the long edges of said first member and foldable over said first member to serve as covers, a foot flap extending along the foot portion of said first member and foldable thereover to serve as a cover, a foldable hood comprising a substantially rectangular element having folds secured to the head portion of said first member to form a hood, a

strap secured to said first member in the general chest area of a body to be supported on said first member and adapted to be secured to a portion of said body for providing traction thereto, a plurality of handles extending from both edges of said first member and formed of webbing extending entirely across said first member for reinforcing said first member, all of said handles being constructed to receive rigid pole members along the edges of said first member in a direction substantially parallel to the longitudinal axis thereof, a second member secured to said first mentioned member along the edges thereof from said foot portion to a point adjacent the head portion to form a pocket for supporting a rigid element, a plurality of webbing strips secured to and extending transversely across said first member and above said flaps for holding a body to be transported on said first member in place, adjustable fastening means on said strips, elements secured to the fabric of said first member for applying traction thereto and additional strip members at the foot portion adjustable in length for supporting the feet of a body to be transported.

5. In a rescue device for supporting a body to be transported comprising a substantially rectangular first member comprising a heavy fabric and having a head portion and a foot portion and converging at the head portion into an apex, a rope extending the full length of said fabric from the foot portion to the head portion to said apex and secured to all the edges of said canvas for reinforcing all the edges and for providing a gripping means at all points thereon, a looped load receiving metallic member at the apex of said first member, a first reinforcing member extending from said load receiving metallic member longitudinally along said first member for distributing the forces exerted on said load receiving metallic member to prevent curling of said first member along its longitudinal center when load is applied thereto, said rope extending to and being secured to said load receiving metallic member for taking a portion of the load, a plurality of reinforcing strips extending angularly from said first reinforcing member for forming handles and also for distributing the load on said load receiving metallic member, a strap secured to said first member in the general chest area of the body to be transported on said first member for securing to a portion of said body for providing traction thereto, a plurality of handles extending from both edges of said first member, all of said handles being constructed to receive rigid pole members along the edges of said first member in a direction substantially parallel to the longitudinal axis thereof, a plurality of strips secured to and extending transversely across said first member and above said flaps for holding the body to be transported in place, adjustable fastening means on said strips, elements secured to said fabric for applying traction thereto and additional strip members at the foot portion adjustable in length for supporting the feet of a body to be transported.

6. In a rescue device for supporting a body to be transported comprising a substantially rectangular first member comprising a heavy fabric and having a head portion and a foot portion and converging at the head portion into an apex, a rope extending the full length of said fabric from the foot portion to the head portion to said apex and secured to all the edges of said canvas for reinforcing all the edges and for providing a gripping means at all points thereon, a looped load receiving metallic member at the apex of said first member, a first reinforcing member extending from said load receiving metallic member longitudinally along said first member for distributing the forces exerted on said load receiving metallic member to prevent curling of said first member along its longitudinal center when load is applied thereto, said rope extending to and being secured to said load receiving metallic member for taking a portion of the load, a plurality of reinforcing strips extending angularly from said first reinforcing member for forming handles and also for distributing the load on said load receiving metallic member, a plurality of handles extending from both edges of said first member for reinforcing said member for

10 and also for distributing the load on said load receiving metallic member, a plurality of handles extending from both edges of said first member, webbing extending entirely across said first member for reinforcing said first member, all of said handles being constructed to receive rigid pole members along the edges of said first member in a direction substantially parallel to the longitudinal axis thereof, and strap members at the foot portion adjustable in length for supporting the feet of a body to be transported.

15 7. In a rescue device for supporting a body to be transported comprising a substantially rectangular first member comprising a fabric and having a head portion and a foot portion and converging at the head portion into an apex, a rope extending the full length of said fabric from the foot portion to the head portion to said apex and secured to all the edges of said fabric for reinforcing all the edges and for providing a gripping means at all points thereon, a load receiving metallic member at the apex of said member, a first reinforcing member extending from said load receiving metallic member longitudinally along said first member for distributing the forces exerted on said load receiving metallic member to prevent curling of said first member along its longitudinal center when load is applied thereto, said rope extending to and being secured to said load receiving metallic member for taking a portion of the load, a plurality of reinforcing strips extending angularly from said first reinforcing member for forming handles and also for distributing the load on said load receiving metallic member, flaps extending along the long edges of said first member and foldable over said first member to serve as covers, a foot flap extending along the foot portion of said first member and foldable thereover to serve as a 20 cover, a foldable hood comprising a substantially rectangular member having folds secured to the head portion of said first member to form a hood, a strap secured to said first member in the general chest area of a body adapted to be transported and securable to a portion of said body for providing traction thereto, a plurality of handles extending from both edges of said first member extending entirely across said first member for reinforcing said first member, all of said handles being constructed to receive rigid pole members along the edges of said 25 first member in a direction substantially parallel to the longitudinal axis thereof, a plurality of strips secured to and extending transversely across said first member and above said flaps for holding the body to be transported in place, adjustable fastening means on said strips, members secured to said fabric for applying traction thereto and additional strip members at the foot portion adjustable in length for supporting the feet of the body to be transported.

30 8. In a rescue device for supporting a body to be transported comprising a substantially rectangular first member comprising a fabric and having a head portion and a foot portion and converging at the head portion into an apex, a rope extending the full length of said fabric from the foot portion to the head portion to said apex and secured to all the edges of said fabric for reinforcing all the edges and for providing a gripping means at all points thereon, a looped load receiving metallic member at the apex of said member, a first reinforcing member extending from said load receiving metallic member longitudinally along said first member for distributing the forces exerted on said load receiving metallic member to prevent curling of said first member along its longitudinal center when load is applied thereto, said rope extending to and being secured to said load receiving metallic member for taking a portion of the load, a plurality of reinforcing strips extending angularly from said first reinforcing member for forming handles and also for distributing the load on said load receiving metallic member, a plurality of handles extending from both edges of said first member for reinforcing said member for

all of said handles being constructed to receive rigid pole members along the edges of said first member in a direction substantially parallel to the longitudinal axis thereof, a plurality of strips secured to and extending transversely across said first member for holding a body adapted to be transported in place, adjustable fastening means on said strips, members secured to said fabric for applying traction therat and additional strip members at the foot portion adjustable in length for supporting the feet of the body to be transported.
